(57) CLAIM

The ornamental design for a perfume bottle with cap, as shown and described.

DESCRIPTION

FIG. 1 is a front view of a perfume bottle with cap; the rear view is a mirror image thereof;

FIG. 2 is a left side view thereof;

FIG. 3 is a right side view thereof; and,

FIG. 4 is a top plan view thereof.

The broken line shown in the drawings is for illustrative purposes only and forms no part of the claimed design.
